UNITED STATES PATENT OFFICE.

GUSTAV A. HARTER, OF CHICAGO, ILLINOIS.

CLUSTER-SOCKET.

No. 854,493.

Specification of Letters Patent.

Patented May 21, 1907.

Application filed November 22, 1906. Serial No. 344,548.

To all whom it may concern:

Be it known that I, GUSTAV A. HARTER, a citizen of the United States, residing at Chicago, in the county of Cook and State of Illinois, have invented certain new and useful Improvements in Cluster - Sockets, of which the following is a specification.

My invention relates to improvements in electric lamp cluster sockets, and has for its 10 salient object to provide a cluster socket which is cheap, easy of manufacture, durable, and attractive in appearance; wherein the parts are positively positioned, so that they cannot possibly become deranged; and 15 wherein substantially perfect insulation of the electrically separated conductive parts is positively insured.

Other and further objects of my invention will best become apparent to those skilled in 20 the art from the following description, taken in conjunction with the accompanying drawings, wherein;

Figure 1 is a section on line 1—1 of Fig. 2. Fig. 2. is a bottom plan view of Fig. 1. Fig. 25 3 is a plan of a modified embodiment, and, Figs. 4. and 5 are sections on lines 4—4 and 5—5 respectively of Fig. 3.

Throughout the drawing like numerals of reference refer always to like parts.

30 In general I provide a cluster lamp socket comprising a body of plastic insulating material of suitable character, such as glass, adapted to be molded when in proper molten condition, such body being suitably and advantageously shaped, and having permanently associated therewith, in inseparable relation thereto, suitable electric lamp socket contacts, connecting electrical conductors, embedded in the insulating body in insulated 35 relation to each other, and exposed terminal extensions of the connectors, properly positioned in the glass body for ready connection with the line wiring.

5 indicates the body of insulating material, 45 such as glass, molded while molten to suitable form, preferably round in plan, and generally convexly curved from its greatest diameter in substantially the top plane to a minimum diameter in substantially the bottom plane 50 thereof. To facilitate the operation of making the cluster, and to lighten and cheapen the construction, the concave shape of the side is maintained only in areas adjacent the lamp sockets, as shown in the drawing at 6, 55 the intermediate areas being reduced in size, as shown at 7, to form depressions between

the areas contiguous to the sockets. In the upper surface of the body is a recess 8 and at its lower surface a central recess 9, communicating with the upper recess through a central aperture 10, and apertures 11. These apertures are provided to permit the structure to be readily secured to any desired support, and to accommodate such line wiring as may be led to the terminals to be described. 60

13—13 indicate the metallic socket shells having inturned flanges 14 at their upper or radially inner extremities, to give said shells strength to resist crushing strain and avoid buckling of said shells in the molding of the 7c article. The sockets 13 are radially arranged, preferably with an inclination downward from a horizontal plane toward their open mouths, and are exteriorly surrounded by the glass body, the interior surfaces of the 75 socket shells being free for the reception of lamps. In the parallel lamp arrangement shown, the socket shells are electrically connected by a bare conductive wire 15 which extends through a generally circular path, 80 into suitable mechanical and electrical connection with each shell, and has its ends twisted together, as shown at 16, and led down through the body of the glass to a suitable point where the wire is looped as shown 85 at 17 to form part of a terminal connection, located within the recess 9 and accessible from the exterior of the appliance. The loop 17 bears upon a bushing 18 embedded in the glass body with only its end surface 90 level with the bottom of the recess 9, said bushing being interiorly screw threaded for the reception of a screw 19, these parts forming convenient terminal binding-posts.

21 indicates the center-contact connector, 95 for all of the sockets, said connector preferably comprising a bare wire embedded in the glass in suitable relation to the socket shells and connector, and having a small area exposed axially within each socket. Preferably the exposed parts of wire 21 lie in recesses 22 in the plastic material body in longitudinal alignment with the axis of the respective sockets. As may be preferred or desired, the exposed portions of the wire 21 105 may be themselves utilized as center contacts, or any suitable metallic contacts, not shown, may be attached thereto.

At some suitable point the ends of the wire 21 are twisted together as at 23, and 110 brought down through the glass body to the top of the recess 9 where the ends are twisted

into a loop 17, seated on a bushing 18, partially embedded in the glass, and receiving a wire-attaching screw 19, in the manner heretofore described in conjunction with the 5 terminal for the shell connector.

In a series lamp cluster, the connections may conveniently be broken between alternate contact points, that is to say, connection being made from the shell of one socket 10 to the shell of the next, from the center of the second socket to the center of the next, from shell to shell again, and so on, or any other scheme of wiring may be used, in any event the terminals being anchored in the glass 15 and exposed for connection with outside wiring.

At suitable points within the recess 9 I provide bosses 25 in which are seated interiorly threaded studs 26, partially embedded in the glass body for permanent attachment, such studs constituting anchorages for screws which may be conveniently employed in attaching to the article a suitable device for covering and concealing the 25 recess 9. In dotted lines in Fig. 1, I have shown at 27 the outline of a snap-switch of a well known pattern, which may be conveniently applied for the purpose of controlling the circuit wherein the cluster may be employed, and at the same time covering and concealing the recess 9 and the exposed electrical contact parts therein.

In Figs. 3, 4 and 5, I have shown an attaching device which I preferably incorporate in my cluster. In said views it will be observed that the body is not recessed as shown at 8 (in Figs. 1 and 2) but is relatively thick throughout its central zone, and that the apertures 11 are also dispensed with. In 35 the top of the body, however, are provided opposite radiating sloping depressions or grooves 28, communicating at their inner, lower ends with the central aperture 10. 30 indicates an attaching fixture comprising a 40 tubular part 31 internally and externally threaded, and made integral with two separated legs 32, 32 straddling the grooves 28, and at their ends provided with outspread feet 33 which are embedded directly in the 45 glass body. Thus the attaching fixture is made part of the unit and affords means for connection of the cluster to a stud internally or externally threaded. The wiring may be led through the fixture 30 or through the 50 grooves 28 and between legs 32 as occasion may require.

While I have herein described in some detail a specific form and construction of my invention which I have found in practice to 55 be advantageous in many respects, I do not desire to be understood as limiting myself to exact details of construction further than as specified in the claims, as it will be apparent to those skilled in the art that numerous 60 changes might be made in the embodiment

of my invention without departure from its spirit and scope.

Having thus described my invention, what I claim and desire to secure by Letters Patent, of the United States, is:

1. As an article of manufacture, a cluster lamp socket comprising a body of insulating plastic material molded to suitable form, and having embedded therein to suitable extent, for inseparable attachment thereto, lamp 75 socket rims, center-contact conductors, electrical connections for the rims and center-contact conductors, and exposed terminals for said connections.

2. As an article of manufacture, a cluster lamp socket comprising a body of plastic insulating material molded into suitable form, a series of radially disposed lamp socket shells exteriorly embedded in said body and 85 interiorly open, a connector for said shells embedded in said body and having an extension led to an exposed terminal position, and a center-contact connector likewise led through the material body to an exposed terminal position.

3. As an article of manufacture, a cluster socket comprising a molded plastic body having socket shells partially embedded therein, a socket-shell connecting wire, an exposed terminal part embedded in said 95 body wherewith the wire is connected, and a center-contact connecting wire led to an exposed terminal.

4. As an article of manufacture, a unitary cluster socket comprising a molded body of plastic insulating material, having permanently associated therewith and molded therein lamp socket shells, partially embedded in the body, a shell connector embedded therein and having a part exteriorly exposed for connection with exterior wiring, a center-contact connector having a part 100 likewise exposed, and screw-threaded studs disposed to receive supports for a covering 105 for the connector terminals.

5. An article of manufacture consisting of a unitary cluster socket for incandescent electric lamps, comprising a molded body of insulating material provided with an externally open recess, said body having embedded therein to suitable extent and permanently secured in positions relative thereto, threaded terminal members arranged in the recess, lamp contacts, and connectors for the lamp contacts extended to the recess in 115 the body and electrically connected with the threaded terminal members.

6. As an article of manufacture, a unitary cluster lamp socket comprising a body of plastic material molded to suitable form, and 125 suitable lamp sockets, contacts, connections, and attachment devices inseparably embedded in the body.

7. As an article of manufacture, a unitary cluster socket comprising a body of plastic 130

insulating material having embedded therein in inseparable connection therewith suitable lamp sockets, contacts, connections, and an attaching part, having a projecting threaded portion.

8. As an article of manufacture, a unitary cluster socket comprising a body of plastic insulating material of suitable configuration having an aperture therethrough, suitable lamp sockets, contacts and connections inseparably associated with the body in molding, and an attaching part comprising a tubular portion, and separated legs straddling the orifice and feet embedded in the plastic body.

9. As an article of manufacture, a cluster lamp socket comprising a body of plastic insulating material molded to suitable form providing lamp-receiving recesses, and having embedded therein to suitable extent for

inseparable attachment thereto lamp contacts suitably positioned with respect to the recesses, electrical connections for said contacts, and exposed terminals for said connections.

10. As an article of manufacture, a unitary cluster socket comprising a body of plastic insulating material, having embedded to suitable extent therein lamp contacts, connections and exposed terminals for said connections, and an attaching part comprising a threaded tubular portion having lateral apertures therein.

In testimony whereof I hereunto set my hand in the presence of two witnesses.

GUSTAV A. HARTER.
